(57) **CLAIM**

The ornamental design for a lavatory, as shown and described.

DESCRIPTION

In a preferred embodiment, this nature of the product is a plumbing fixture, such as a pedestal sink, for washing human body parts.

FIG. 1 is a top, front perspective view of a lavatory showing my new design;

FIG. 2 is a top plan view thereof;

FIG. 3 is a front elevation view thereof;

FIG. 4 is a left side elevation view, the right side being a mirror image thereof;

FIG. 5 is a rear elevation view thereof; and,

FIG. 6 is a bottom plan view thereof.

The broken line representations of holes and sink bowl in FIGS. 1-2 and underside and rear features in FIGS. 5 and 6 are for the purpose of illustration only, and form no part of the claimed design.
